STORAGE RACK

Roy G. Kramer, 1342 Signal Drive,
Pomona, Calif. 91767

Filed Dec. 18, 1972, Ser. No. 316,089

Term of patent 14 years

Int. Cl. D6—04

U.S. Cl. D6—130

FIG. 1.

FIG. 2.

FIG. 3.

FIG. 1 is an isometric view, showing my new design;
FIG. 2 is an end view thereof; and
FIG. 3 is a bottom view thereof.

The end not shown is a mirror image of the end shown in FIG. 2.

I claim:

The ornamental design for a storage rack, as shown and described.
